UNITED STATES PATENT OFFICE

2,045,279

ADJUSTABLE NECKTIE

William Mayer, New York, N. Y.

Application July 26, 1935, Serial No. 33,284

3 Claims. (Cl. 2—155)

My present invention relates generally to neckwear, and has reference to an improved type of adjustable neckband.

It is a general object of my invention to provide an improved adjustable necktie, of the general character illustrated in United States Letters Patent No. 2,003,359, issued June 4, 1935. This type of necktie has a neckband portion which is adjustable in length by doubling it back upon itself and by providing at its end a hook which is adapted to engage with a selected one of a series of openings or perforations in the neckband.

The more specific objects of the present invention include an improved mode of assembly of various elements, whereby the outward appearance of the necktie is more attractive, whereby the construction is more compact and easier to slip through or under a collar, and whereby the adjustable feature is coupled with a maximum display of attractive tie material.

In accordance with my present invention, the neckband portion consists of inner and outer plies of relatively delicate tie material, and the construction is of a character which leaves the tie material exposed throughout the length of the neckband. This desirable result is achieved notwithstanding the provision, in the neckband, of a series of spaced perforations permitting the length of the neckband to be adjusted as hereinbefore mentioned; and the present invention provides a unique method for reinforcing the relatively delicate tie material.

Briefly, my present invention provides for the association, with the inner ply of the neckband, of a reinforcement band, which is disposed on the inside of the inner ply so as to be totally concealed from view. The reinforcement band has a series of perforations which register with a similar set of perforations in the tie material itself; and means are provided for marginally interengaging each pair of registering perforations so as to secure the reinforcement band in position without the necessity for the use of adhesive or unsightly stitching.

I achieve the foregoing objects, and such other objects as may hereinafter appear or be pointed out, in the manner illustratively exemplified in the accompanying drawing, wherein—

Figure 1 is a perspective view of a tie of the "ready-made" variety, embodying the features of the present invention;

Figure 2 is an enlarged cross-sectional view taken substantially along the line 2—2 of Figure 1;

Figure 3 is a fragmentary perspective view of the inner ply of the neckband, shown by itself;

Figure 4 is a perspective view showing the manner in which the present invention may be applied to the type of tie that is not "ready-made"; and

Figure 5 is a perspective view showing the manner in which the invention is adapted to a four-in-hand type of tie.

The "ready-made" type of bow tie embodies the bow 10 and the preformed knot 11. Extending in opposite directions from the rear of the knot 11 are the neckband portions 12 and 13. The neckband of the tie is made adjustable in length by providing a hook 14 or equivalent male fastening element at the extremity of the neckband portion 13, whereby this portion may be doubled back upon itself to engage the hook in any one of a series of perforations provided in a predetermined arrangement. A metallic loop 15 is slidably mounted on the neckband portion 13 and is adapted to be engaged at its midportion by a hook 16 that is carried at the extremity of the neckband portion 12.

The manner of applying the hooks 14 and 16 to the extremities of the neckband portions has not been illustrated in detail, because these particular portions of the structure have no bearing upon the present invention.

In accordance with the present unique mode of constructing and assembling the parts, the neckband portion 13 is composed of the inner and outer plies 17 and 18. Each ply is made of relatively delicate and ornamental tie material, and in the finished assembly the longitudinal edge portions of these plies are turned inwardly and are stitched together, as at 19. As will be understood by those skilled in the art, this requires that the plies 17 and 18 be first assembled back to back, and then, after stitching them together, the entire assembly is turned inside out.

In accordance with my present invention, the inner ply 17 is provided with the longitudinally spaced perforations 20 which are arranged along the midportion of the ply at predetermined distances from one another, the location of these perforations being such that the neckband as a whole may be adjusted to different neckband or collar sizes.

In carrying out the present invention, a reinforcement band 21, of somewhat narrower width than that of the ply 17, is provided with a series of perforations 22 which are arranged in longitudinally spaced relation along the midportion

of the band 21. The perforations 22 are spaced apart by amounts corresponding to the spaces between the perforations 20, so that when the band 21 is associated with the underside of the 5 ply 17 the perforations 20 and 22 are in registry.

The band 21 may be of any suitable staunch material, and it is preferably selvaged along its longitudinal edges 23, the term "selvage" being intended to refer to the type of selvage which is 10 usually provided by weaving during the manufacture of the fabric, whereby the resultant product is of single ply substantially uniform thickness throughout.

When the band 21 is associated with the underside of the ply 17, each pair of registering perforations is marginally interengaged. One way of accomplishing this is to provide a "buttonhole" type of stitching 24 to each pair of perforations. This fastening means retains the 15 perforations 20 and 22 in alignment and registry, and serves at the same time to secure the reinforcement band 21 to the ply 17 in a firm and efficient manner. I draw attention to the fact that no adhesive is required between the band 20 and the ply 17; nor are any stitches, other than the stitches 24 (or the equivalent thereof), needed to hold the parts in proper associated relationship. This fact, coupled with the single ply 25 selvaged nature of the reinforcement band 21, produces an assembly which is uniquely compact and attractive. As shown in Figure 2, it will be observed that the band 21 is in completely concealed position, and upon viewing that portion of Figure 3 which is disposed toward the right, and 30 also Figure 1, it will be seen that the exterior exposed surface of the neckband is composed wholly of the ornamental tie fabric.

In thickness, the neckband is compact and uniform, devoid of any medial bulkiness, and 40 well adapted for smooth and easy passage through or around the collar with which the tie is to be worn.

At the same time, the neckband is adjustable, as hereinbefore described, and when the hook 45 14 is inserted into any selected perforation, no undue strain is applied to the relatively delicate tie fabric, any tension or stress being taken up and borne by the reinforcement band 21.

As hereinbefore described, the plies 17 and 18 50 are stitched together back to back, when the tie is manufactured. In carrying out the present invention, the reinforcement band 21 is first associated with the ply 17, as shown in Figure 3; and when the plies 17 and 18 are stitched together, the band 21 is disposed outwardly. Then, 55 when the tubular construction is turned inside out, the parts assume the relationship shown in Figure 2.

Inasmuch as the perforations do not extend 60 for the full length of the neckband portion 13, it may be desirable, under certain circumstances, to construct the ply 17 initially of two parts. This possibility I have illustrated in Figure 4, wherein the inner ply consists of the forward 65 portion 25 and the rearward portion 26. The rearward portion 26 is first perforated and associated with the reinforcement band hereinbefore described; the two portions 25 and 26 are then united end to end; and the resultant assembly 70 is then stitched, in back to back relationship, to the outer unitary ply 27. The tubular construction is then turned inside out. It will be understood, however, that the portion 26 is of exactly the same material as the portion 25, viz., of relatively delicate tie fabric, and that the finished 75

construction displays this tie fabric throughout the entire length of the neckband.

Figure 4 also illustrates the manner in which the invention is applied, with equal facility, to a tie that is not of the ready-made variety. No 5 preformed knot is present in this construction, and the unperforated neckband portion is permanently secured, as at 28, to a metallic elongated ring through which the other neckband portion slidably extends. The extremity of the 10 perforated neckband portion is provided with a hook 29 which corresponds to the hook 15 of Figure 1.

In Figure 5, the invention is shown applied to a ready-made four-in-hand type of tie, and detailed description of this figure is not believed to be necessary, since it will be obvious that the features described in connection with Figures 1-3 are exactly the same in Figure 5 except for the fact that the knot 30 is a four-in-hand type 20 of knot instead of a bow knot.

It will also be understood that the invention is applicable to a regular four-in-hand tie, the tie in such a case being substantially identical with the tie illustrated in Figure 4, except that the 25 ends are considerably longer and are shaped in the conventional four-in-hand manner.

It will be obvious that changes in the details, herein described and illustrated for the purpose of explaining the nature of my invention, may be made by those skilled in the art without departing from the spirit and scope of the invention as expressed in the appended claims. It is, therefore, intended that these details be interpreted as illustrative, and not in a limiting sense. 35

Having thus described my invention, and illustrated its use, what I claim as new and desire to secure by Letters Patent is—

1. In an adjustable necktie, a neckband portion comprising inner and outer plies of relatively 40 delicate tie material, said plies having their longitudinal edges turned inwardly and stitched together by concealed stitching the inner ply having a series of perforations arranged in predetermined longitudinally spaced relation, said 45 neckband portion being adapted to be doubled back upon itself and provided at its end with a male fastening element adapted to engage with a selected perforation, a reinforcement band of relatively staunch material arranged on the inside surface of said inner ply, said band having perforations registering with those in said inner 50 ply, and means marginally interengaging each pair of registering perforations for securing the reinforcement band in position. 55

2. In an adjustable necktie, a neckband portion comprising inner and outer plies of relatively delicate tie material, said plies having their longitudinal edges turned inwardly and stitched together by concealed stitching the inner ply having a series of perforations arranged in predetermined longitudinally spaced relation, said neckband portion being adapted to be doubled back upon itself and provided at its end with a male fastening element adapted to engage with a selected perforation, a reinforcement band of relatively staunch material arranged on the inside surface of said inner ply, said band having perforations registering with those in said inner 60 ply, and means marginally interengaging each pair of registering perforations for securing the reinforcement band in position, said band being otherwise entirely free of connection with the necktie. 75

3. In an adjustable necktie, a neckband portion comprising inner and outer plies of relatively delicate tie material, said plies having their longitudinal edges turned inwardly and stitched together by concealed stitching the inner ply having a series of perforations arranged in predetermined longitudinally spaced relation, said neckband portion being adapted to be doubled back upon itself and provided at its end with a male fastening element adapted to engage with

a selected perforation, a reinforcement band of relatively staunch material arranged on the inside surface of said inner ply, said band having a selvage on each longitudinal edge and having perforations registering with those in said inner ply, and means marginally interengaging each pair of registering perforations, said band being otherwise entirely free of connection with the necktie. 5

WILLIAM MAYER. 10
